UNITED STATES PATENT OFFICE

FREDERICK M. FRIEDRICH, OF SUMMERTOWN, SOUTH CAROLINA

RADIO SECRETARY

Application filed April 6, 1932. Serial No. 603,645.

This invention relates to a radio secretary which can be used with any radio cabinet that stands on the floor, the general object of the invention being to provide a compartment in the lower part of the cabinet normally closed by a door which can be raised and held in a horizontal position so that the door can be used as a shelf or as a desk.

10 This invention also consists in certain other features of construction and in the combination and arrangement of the several parts to be hereinafter fully described, illustrated in the accompanying drawings and specifically pointed out in the appended claim.

15 In describing the invention in detail, reference will be had to the accompanying drawings wherein like characters denote like or corresponding parts throughout the several views, and in which:—

20 Fig. 1 is a front view of the invention.

Fig. 2 is a view of the lower part thereof showing the door in raised position.

25 Fig. 3 is a vertical sectional view through the lower part of the cabinet with the door in closed position in full lines and shown in two of its horizontal positions in dotted lines.

Fig. 4 is a section on line 4—4 of Fig. 1.

Fig. 5 is a horizontal sectional view with the door in raised position.

30 Fig. 6 is a view of the door.

Fig. 7 is a fragmentary view of the door with parts removed to show the latch means.

Fig. 8 is a sectional view through the door showing the latch means.

35 Fig. 9 is a detail vertical sectional view showing the latch means.

Fig. 10 is a fragmentary edge view of that part of the door through which the latch means projects.

40 In these drawings, the letter A indicates the radio cabinet as a whole and the letter B indicates the compartment formed in the lower part of the cabinet and which may contain the shelves 1 and the drawers 2. A door

45 C is provided for closing the front of the compartment and said door has a pair of pins 3, one in each side edge thereof, and adjacent one end thereof, the pins being located adjacent that end of the door which is lowermost when the door is in closing position.

Guideways 4 are formed in the inner faces of the front corner members 5 of the cabinet for receiving the pins, and horizontal guideways 6 are formed in the side members 7 extending horizontally from front to rear at the top of the compartment B. The front ends of these guideways 6 communicate with the upper ends of the guideways 4 so that by swinging the door downwardly into horizontal position and then moving the door upwardly, the pins 3 will pass upwardly through the guideways 4 and then by pushing the door inwardly the pins will pass into the guideways 6.

The door is formed with an opening 8 which extends from one side edge of the door through the other side thereof and substantially at the center of the door and is preferably of the shape shown in Fig. 7. If desired, the door can be formed of inner and outer sections suitably fastened together with the opening 8 formed in the adjacent faces of the two sections.

A bushing 9 is placed in each end of the opening. A knob or handle 10 is rotatably supported by a plate 11 attached to the central part of the front face of the door and covering an opening which communicates with the opening 8 and said handle has a cross piece 12 connected to its inner end. A rod 13 has its inner end pivoted to each end of the cross piece 12 and said rods pass through the bushings 9 when the rods are projected and their outer ends will be slightly drawn within the bushings when the rods are moved inwardly by the turning of the cross piece by the handle. The projected ends of the rods 13 will engage the guideways 4 when the door is in vertical position to lock the door in this position and by turning the handle in a certain direction the rods will be moved inwardly so that the door can be swung downwardly and then when it reaches horizontal position, it can be moved upwardly, still in a horizontal position and then moved inwardly to cause the pins 3 to engage the guideways 6.

Then by projecting the rods 13 so that their outer ends will engage the guideways 6, the door will be held in horizontal position.

so that it can be used as a shelf or as a desk.

It is thought from the foregoing description that the advantages and novel features of the invention will be readily apparent.

5 It is to be understood that changes may be made in the construction and in the combination and arrangement of the several parts provided that such changes fall within the scope of the appended claim.

10 Having thus described my invention what I claim as new is:

A cabinet having a compartment therein, with an opening at the front of the compartment, the side walls of the opening having 15 vertical guideways therein and the side walls of the compartment having horizontally arranged guideways therein adjacent the top of the compartment, the outer ends of which are in communication with the upper ends 20 of the first-mentioned guideways, a door having pins in its side edges adjacent the lower end of the door for fitting in the guideways, whereby the door can be swung downwardly and outwardly and then moved upwardly to cause the pins to pass upwardly 25 through the vertical guideways until they come into alignment with the horizontal guideways, after which the door can be moved inwardly to cause the pins to enter 30 the horizontal guideways and bolt means carried by the door and engaging the horizontal guideways, when projected to support the door in a horizontal position with a part projecting forwardly from the cabinet to 35 form a shelf or desk, the said bolt means, when projected, with the door in vertical position for closing the opening, engaging the vertical guideways for holding the door in closing position.

40 In testimony whereof I affix my signature.
FREDERICK M. FRIEDRICH.
